UNITED STATES PATENT OFFICE.

JINGORO HINO AND KIYOTAKA SHINDO, OF CHICAGO, ILLINOIS.

CARD GAME.

Application filed April 3, 1924. Serial No. 703,975.

To all whom it may concern:

Be it known that we, JINGORO HINO and KIYOTAKA SHINDO, subjects of the Emperor of Japan, residing at Chicago, in the county of Cook and State of Illinois, have invented a certain new and useful Improvement in Card Games, of which the following is a full, clear, concise, and exact description, reference being had to the accompanying drawings, forming a part of this specification.

Our invention relates to games and more particularly to a card game.

The card game comprises a deck of cards made up of a plurality of groups, certain of which have similar characteristics and certain of which have dis-similar characteristics both from each other and from the groups having the same characteristics.

The cards preferably have indicating means thereon to indicate the value of the cards. Further, the cards preferably have characters or symbols thereon for indicating the value of the cards and the suit or group to which the cards belong. The symbols vary in accordance with the value of the cards in one characteristic but all the symbols or illustrations relating to one suit have common characteristics to distinguish that suit from the other suits.

It is a purpose of the invention to provide cards for playing card games that constitute groups as set forth above and having the characteristics set forth above, certain of which cards are, in addition, provided with supplemental symbols or indicating means to indicate individual cards in certain of the groups, these individual cards together again forming other groups independent of the first groups. That is, a card taken from one group, a card taken from a second group and a card taken from a third group each have a certain symbol or indicating means thereon to indicate that these cards together form a group or are related to each other.

The game further comprises a plurality of said last mentioned groups of cards that have symbols or indicating means thereon to distinguish the cards of one of said last mentioned groups from the cards of another of said last mentioned groups.

Due to the irregular arrangement of the cards in groups or suits with different values attached to the cards of the different groups in certain cases and with the same values

attached to the cards of some of the groups in other cases and with the additional grouping of the cards, due to the supplemental symbols referred to, there is a much greater variety of combinations of cards or groups of cards obtainable from such an arrangement, than with the ordinary deck of playing cards in which the corresponding cards of the four suits have the same values and in which the arrangement of the cards in each suit is the same, thus giving greater variety to the game and also providing a greater element of chance in the game.

Other objects and advantages of the invention will appear as the description of the accompanying drawings proceeds. However, we desire to have it distinctly understood that we do not intend to limit ourselves to the exact details shown or described but that we intend to include as part of our invention all such obvious changes and modifications of parts as would occur to a person skilled in this art and as would fall within the scope of the claims.

In the drawings is shown a plurality of the cards constituting the deck sufficient to illustrate the differences between the cards comprising the deck, the entire deck not being shown because of the large amount of space required to illustrate the entire deck of cards.

Referring in detail to the drawings, the deck of cards comprises preferably 48 cards comprising 12 groups or suits each having four cards therein. The various groups of cards each comprise a plurality of cards of differing values although in some cases two cards of one group have the same value and in some cases more than two cards of the same group have the same value, but in no case do all the cards of any one group have the same value.

The cards are indicated in the drawings by the numerals 21 to 44 inclusive and each of said cards is provided with indicating numerals in the corners thereof, as will be clear from the drawings. For example, the cards numbered 21 have the numerals 1 in the corners thereof to indicate the value of the card and, in addition, have a character or symbol thereon to indicate to what suit these cards belong. The symbol or character may be of any nature but is indicated in the drawings as a letter of the alphabet. Thus, the character A is applied to the cards 21, 22

and 23, which constitute a suit or group. The illustrations may be varied in accordance with the value of the card. For example, the card with the numeral 5 thereon, 5 such as the card 22, is shown with the character A underlined to indicate a difference in value between itself and the card 21, and further, the card 23, which is provided with the numeral 20 in the corners thereof, has 10 a complete border around the letter A to indicate a value corresponding to the numeral 20. Each suit or group is indicated by a different symbol or illustrative character or illustration. Thus, for example, the 15 card 24 is shown to illustrate the second group of cards of the deck and carries the character B thereon. Only one card of this suit or group is shown as this suit or group comprises cards similar to one of the other 20 groups. The group designated by the character B, of which the card 24 forms a part, corresponds to the group comprising the cards 26, 27 and 28, this group having two 25 cards of the same value having the indicating numeral 1 thereon, which are designated by the numeral 26, a card 27 having a different value with the indicating numeral 5 in the corners thereof, and a card 28 having a still different value with the indicating 30 numeral 10 in the corners thereof.

The group comprising the cards 29, 30 and 31 also comprises two cards of the same value having the indicating numerals 1 thereon, a card of the same value as the card 35 27 having the indicating numeral 5 thereon and a card of the same value as the card 28 having the indicating numeral 10 thereon, these being designated respectively by the numerals 31, 30 and 29.

40 The group comprising the cards 26, 27 and 28 carries a distinctive character such as the letter D thereon and each of these cards has a variation in the character corresponding to the value of the card. Thus, 45 the card 27 has the D underlined and the card 28 has a partial border around the D to indicate a different value for this card than the card carrying the numeral 5 and to indicate still a different value than a card 50 bearing the numeral 20, such as the card 23.

The card 25 is shown to illustrate the third group of cards which is designated by the character C merely for illustrative purposes. It will be noted that the card 25 and 55 the card 22 have numerous similar characteristics and that these cards include a supplemental symbol providing a variation still different from those above referred to. The cards 22 and 25 each bear the numerals 5 in 60 the corners thereof, each have a main symbol thereon which is similar and each carries an additional symbol indicated by the numeral 47, this being shown as being in the form of a bow of ribbon of a distinctive 65 color, the color being illustrated as being

red in the drawings. While only two cards having these similar symbols thereon are shown, in the complete deck there are three cards belonging to the red ribbon group.

The group represented by the card 25 70 bearing the character C is made up of four cards having the values shown for the group A.

The group indicated by the character E, 75 comprising the cards 29, 30 and 31, is similar to the group D and the group represented by the card 33 bearing the character G, and the group illustrated by the card 38 bearing the character J are the same in arrangement and in relative value as the 80 group comprising the cards 26, 27 and 28 and the group comprising the cards 29, 30 and 31, and for this reason the complete group is not illustrated.

The group illustrated by the card 32 is 85 similar to these groups except that the card of this group bearing the numeral 5, which is the illustrated card, has a bow of ribbon provided thereon of a different color than the bow 47, this bow being indicated by the numeral 48 and being shown in the drawings as being blue. The card 37, representing the group carrying the character I, also is provided with a symbol 48 in the 90 form of a bow of ribbon which is also of the same color as that of the card 32. There are three cards in the complete deck belonging to this group each having a ribbon of the same color, such as blue, thereon but differing in color from that carried 95 by the group of cards comprising the cards 22 and 25.

It will be noted that the first group described, or that carrying the character A, is different from the groups referred to 105 above in that instead of having cards bearing the numerals 1, 5 and 10 to indicate the relative values of the cards, this group comprises cards bearing the numerals 1, 1, 5 and 20.

The group comprising the cards 34, 35 and 36 is dis-similar from any of the groups mentioned above in that it includes two cards 36 bearing the numeral 1, a card 35 bearing the numeral 10 and a card 34 bearing the numeral 20, this group being provided with a suitable symbol, such as the character H, to indicate the group modified to indicate the cards of different 115 value in a similar manner to the corresponding cards in the groups designated by the characters A and D.

The group comprising the cards 39, 40, 120 41 and 42 differs from any of the groups mentioned above in that it comprises only one card of each value, that is, the card 42 has the numeral 1 thereon to indicate the value thereof, the card 41 has the numeral 5 thereon indicating the value thereof, the card 40 has the numeral 10 thereon to indi- 125 130

cate the value thereof and the card 39 has the numeral 20 thereon to indicate the value thereof.

The group comprising the cards 43 and 44 comprises three cards 44 that are alike each bearing the numeral 1 and one different card 43 bearing the numeral 20. The group comprising the cards 39, 40, 41 and 42 carries the symbol K and the group comprising the cards 43 and 44 carries the character L as a symbol to indicate the group.

While numerous games can be played with the cards described above, only one of these games is described below as it would be impossible to describe the large number of games that can be played. The game to be described is known as "High Point" which is, perhaps, the simplest game that can be played with these cards.

The game is played with two or more persons and the cards are dealt in much the same manner as in the well known card games played in this country, although the present game is patterned somewhat after an ancient Japanese game. The game is ordinarily played with some sort of counters such as chips and the dealer is determined on beginning to play the game, the person drawing the card having the highest number dealing. Below is explained the game as played by three players.

In dealing the cards they are dealt one at a time in a clockwise direction about the table until each person has seven cards. Six cards are then taken from the deck and laid on the table face up and the remainder of the deck is placed on the table with the backs up. The dealer then begins to play. In case there are four cards of the same kind on the table, that is, belonging to the same group, face up, it is a misdeal and the cards are dealt over again. If three cards of the same group are face up on the table a player who has the fourth card of the group can take the entire group of three cards off the table.

If there is one card on the table of the same group as one held in the hand of the dealer or other player the player places the card that he has in his hand on the card belonging to the same group on the table and takes them and places them in front of his place at the table. Then the player draws a card from the remainder of the deck that has been placed on the table and sees if he can match this card with a card on the table. If so, he plays in the same manner as before. Otherwise, he places the card face up on the table along with the others. The next player, clockwise around the table then plays in the same manner.

In case the dealer or any other player has no card in his hand of the same group as one of the cards on the table, then the player

places a card face up on the table out of his hand that is of as low a value as he can find in his hand. Then he draws a card from the pile on the table and in case it belongs to a group that is on the table the player can take both of the cards of the same group. If he can not do this, he leaves the card on the table face up, as explained above. The next player, in a clockwise direction then plays in the same manner. As there are 48 cards, six on the table, twenty-one in the hands of the players and twenty-one in the deck on the table when play begins, each player plays seven times in each game. The game continues, of course, until all of the cards have been played.

The numbers in the corners of the cards indicate the points in value that each of the cards carries. The total number of points on all the cards is 264. Accordingly, if three players are playing, if each acquires the same number of points they would each have 88. Anyone having more than 88 points collects the number of counters or chips above 88 from the other players and the players that have less than 88 points have to pay the player having more than 88 points the deficiency between 88 points and the total number of points that they have acquired.

In case any player, while the game is being played, should acquire three red ribbons, three blue ribbons or four of the 20 point cards, which are known as "greats", the game is over and the player who acquires any of the three ribbons or the four greats is the winner of this game and receives 200 points for the three red ribbons from each of the other players, 200 points for the three blue ribbons from each of the other players and 300 points from each of the other players for the four greats. The next game is played the same way except that the winner of the last played game is the dealer for the next succeeding game.

The ancient Japanese game, after which the above described game is patterned, is ordinarily illustrated in such a manner that each group of cards represents a month of the year, that is, the group A represents January, B represents February, C. March, D April, E May, F June, G July, H August, I September, J October, K November and L December, and a complete game in the ancient Japanese game comprises 12 deals, one corresponding to each of the months of the year. The above described game is patterned after the Japanese game referred to to the extent that 12 hands or deals are played to play a complete game.

Having thus described our invention what we desire to claim and secure by United States Letters Patent is:

1. In a card game, a plurality of cards having means thereon for indicating the

- values of said cards, said cards comprising groups having similar indicating means thereon, each of said groups comprising a pair of cards having the same indicating means and a pair of cards having different indicating means, and other groups having different indicating means thereon than those of said first mentioned groups.
5. In a card game, a plurality of cards having means thereon for indicating the values of said cards, said cards comprising groups having similar indicating means thereon and groups having different indicating means thereon, each card having a symbol thereon, the symbols of each group being similar but varying in accordance with the values of the cards.
10. In a card game, a plurality of cards having means thereon for indicating the values of said cards, said cards comprising groups having similar indicating means thereon and groups each having indicating means thereon differing from the indicating means of all the other groups, each card having a symbol thereon, the symbols of each group being similar.
15. In a card game, a plurality of cards having means thereon for indicating the values of said cards, said cards comprising groups having similar indicating means thereon, each of said groups comprising a pair of cards having the same indicating means and a pair of cards having different indicating means, and other groups having different indicating means thereon than those of said first mentioned groups, each card having a symbol thereon, the symbols

of each group being similar, the cards having the same indicating means having the same symbol thereon.

40 5. In a card game, a plurality of cards having means thereon for indicating the values of said cards, said cards comprising groups having similar indicating means thereon and groups having different indicating means thereon, a single card in each of a plurality of groups having a supplemental symbol thereon.

45 6. In a card game, a plurality of cards having means thereon for indicating the values of said cards, said cards comprising groups having similar indicating means thereon and groups having different indicating means thereon, a single card in each of a plurality of groups having a supplemental symbol thereon, said symbols being of two different kinds.

50 7. In a card game, a plurality of cards having means thereon for indicating the values of said cards, said cards comprising groups having similar indicating means thereon and groups having different indicating means thereon, a single card in each of a plurality of groups having a supplemental symbol thereon, said supplemental symbols being of two kinds, there being a plurality of cards provided with each of said two kinds of supplemental symbols.

55 In witness whereof, we hereunto subscribe our names this 8th day of March, A. D., 1924.

JINGORO HINO.
KIYOTAKA SHINDO.
